UNITED STATES PATENT OFFICE

164,200

BED

Jasper M. Rowland, Larchmont, N. Y.

Application July 9, 1949, Serial No. 3,820

Term of patent 14 years

(Cl. D5—4)

To all whom it may concern:

Be it known that I, Jasper M. Rowland, a citizen of the United States, residing at Larchmont, State of New York, have invented a new, original, and ornamental Design for a Bed, of which the following is a specification, reference being had to the accompanying drawing, forming a part thereof.

Fig. 1 is a perspective view of a bed;

Fig. 2 is a top plan view of the bed shown in Fig. 1.

The other side of the body portion of the bed is similar to that shown and the rear portion of the headboard is plain.

I claim:

The ornamental design for a bed, as shown and described.

JASPER M. ROWLAND.
